UNITED STATES PATENT OFFICE.

HENRY B. NORTON, OF MINNEAPOLIS, MINNESOTA.

CLOTHES-LINE FASTENER AND STRETCHER.

No. 839,628.

Specification of Letters Patent.

Patented Dec. 25, 1906.

Application filed April 4, 1906. Serial No. 309,841.

To all whom it may concern:

Be it known that I, HENRY B. NORTON, a citizen of the United States, residing at Minneapolis, in the county of Hennepin and State of Minnesota, have invented certain new and useful Improvements in Clothes-Line Fasteners and Stretchers; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in clothes-line fasteners; and the object of the invention is to produce an apparatus of this nature which will be automatic in its action and comprises a pivotal cam member mounted upon a plate which is detachably held upon a fixed socket member.

The invention consists, further, in various details of construction and combinations and arrangements of parts which will be herein-after fully described and then specifically defined in the appended claims.

My invention is illustrated in the accompanying drawings, in which—
Figure 1 is a side elevation of the socket member adapted to carry the cam-holding plate. Fig. 1^a is a sectional view on line x x of Fig. 1. Fig. 2 is a face view of the cam-holding member. Fig. 2^b is a side elevation of the plate, cam, and rope, said cam being shown in a clamping relation by dotted lines, Fig. 2^b also showing the rope in dotted lines in the position it would assume when being held by the clamp. Fig. 3 is a detail face view of the cam. Fig. 3^a is a side elevation of the cam. Fig. 3^b is an end view of the cam, and Fig. 4 is a side elevation of the various parts assembled.

Reference now being had to the details of the drawings, A designates a socket-plate having an opening a formed in the lower portion thereof, and a' designates screws which are passed through the socket member and adapted to hold the same to a fixed object, such as a post or otherwise. The upper por-

tion of said socket member is recessed, as at A², and has two outwardly-curved arms A³. B designates a T-shaped plate having the laterally-projecting wings B', adapted to engage the shoulders A⁴ behind the arms A³, 55 and B² designates lugs projecting from the opposite edges of the plate B, and B³ is a pin carried in apertures in said lugs upon which a cam C is pivotally mounted. The lower end of the plate B is constricted and is 60 slightly curved, as seen clearly in Figs. 2, 2^b, and 4 of the drawings, and the lower end of said plate is adapted to engage the aperture a in the socket member A, as shown in dotted lines in Fig. 4. 65

D designates a rope which rests in the groove C', formed in the upper edge of the cam member, which serrated edge is preferably milled or provided with a roughened surface, and the rope passes between the cam 70 and the plate supporting the latter and bearing against the convexed surface of the cam, as shown in Fig. 2^b of the drawings. When the line is weighted, it will be observed that the roughened surface of the cam will be 75 caused to frictionally engage and clamp the rope against the plate, thereby securely holding the rope from slipping. It will thus be seen that the tightening of the rope will be 80 entirely automatic, as when it is desired to tighten the same a person merely pulls down upon the end of the rope below the cam, and the cam will automatically loosen to allow the slack to be taken up, and the extra strain 85 coming upon the outer end of the cam after the latter has been brought taut will hold the latter from slipping.

What I claim is—

1. A clothes-line holder comprising a socket member designed to be attached to a 90 wall or other fixed object, said member having a recess at its upper end and forwardly-extending arms, a plate having laterally-projecting portions adapted to rest upon shoulders behind said arms, lugs upon said plate, 95 and a cam pivotally mounted upon said lugs, as set forth.

2. A clothes-line holder comprising a socket member designed to be attached to a wall or other fixed object, said member hav- 100

ing a recess at its upper end and forwardly-extending arms, a plate having laterally-projecting portions adapted to rest upon shoulders behind said arms, the lower portion of said plate being constricted and curved and adapted to engage an aperture in said socket member, lugs projecting from said plate, a

cam member mounted upon said pin, as set forth.

In testimony whereof I hereunto affix my signature in the presence of two witnesses.

HENRY B. NORTON.
